UNITED STATES PATENT OFFICE.

GEORGE A. LEONARD, OF SHEFFIELD, IOWA.

SILO-DOOR.

1,123,560.

Specification of Letters Patent.

Patented Jan. 5, 1915.

Application filed March 14, 1914. Serial No. 824,767.

To all whom it may concern:

Be it known that I, GEORGE A. LEONARD, a citizen of the United States, residing at Sheffield, in the county of Franklin and 5 State of Iowa, have invented a new and useful Silo-Door, of which the following is a specification.

This invention relates to doors for silos and the like, one of its objects being to provide a door which is constantly connected to the door frame whether said door is in open or closed position, the means utilized for connecting the door to the frame being designed for use as a portion of a ladder.

15 A further object is to provide a silo door which, when moved out of closed position, can not drop below the door opening but will be supported at a point where it can be conveniently reached from the outside 20 for the purpose of shifting it to its completely open position.

A further object is to provide means whereby the door, when completely opened, will be held securely against displacement, 25 the holding means being simple, durable and efficient.

A further object is to provide means whereby the holding means can be readily disengaged by a person outside of the silo 30 when it is desired to lower the door to its closed position.

Another object is to provide a member for use in disengaging the elevated silo door, 35 said member, when the door is closed, constituting a portion of a ladder.

A further object is to provide means for locking the door when closed, said means being so constructed and mounted as to prevent the door from closing and locking accidentally while a person is within the silo.

With the foregoing and other objects in view which will appear as the description proceeds, the invention resides in the combination and arrangement of parts and in 45 the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front elevation of a portion of a silo and showing one 55 of the doors such as constitutes the present

invention, in closed position. Fig. 2 is a section on line A—B Fig. 1. Fig. 3 is a section on line C—D Fig. 1. Fig. 4 is a vertical section through two silo doors, one of them being shown raised and secured in open position and the other door being shown in closed position.

Referring to the figures by characters of reference 1 designates a substantially rectangular frame preferably formed in a single casting and, in erecting a silo, a number of these frames are to be used, the same being placed one upon the other as indicated in Figs. 1, 3 and 4. Said frame can be of any preferred cross sectional contour but are preferably channeled in the outer sides thereof as shown at 2 so as to receive the blocks 3 or other elements constituting the wall of the silo, and which may be fastened to the sides of the door frame in any suitable manner.

The door frame has an inwardly extending flange 4 along each side thereof provided with an inner beveled face 5 and another similar flange 6 is formed upon the bottom of the door frame and another like flange 7 depends from the top of the door frame. These flanges 6 and 7 are also provided with inner beveled faces 8.

Formed upon the front faces of the flanges 4 near their upper ends are lugs 9 provided with sockets 10 and extending inwardly and upwardly back of and above the lugs 9 are ears 11 forming seats 12.

A bail 13 is mounted within each door frame and the arms 14 of this bail have outwardly turned terminals 15 which are slidably and revolvably mounted within the lugs 9. Each arm 14 is provided, at a point between its ends, with a portion 16 inturned abruptly to form a shoulder or abutment 17 and merging into a deflecting portion 18 which is obliquely disposed relative to the arms 14, as shown particularly in Fig. 1. These inwardly extended portions 16—17 of the arms 14 constitute supports for a cross bar 19 preferably formed with an eye 20 at one end for engaging one of the inwardly extended portions and with a loop 21 at its other end for engaging the opposed inwardly extended portion. This bar 19 is supported under normal conditions by the inwardly extended portion 16 and, when the door of the silo is closed, the said bar 19 forms a rung of a ladder.

The intermediate portion 22 of the bail 13 is offset for the greater portion of its length to form an outstanding yoke 23 and those portions of the bail between the yoke 3 and the arms 14 are mounted in brackets 24 which are secured to the outer face of a door 25 preferably close to the lower edge of the door. When the door is closed, this outstanding yoke 23 forms a rung of a ladder as will be apparent.

The edges of the door 25 are preferably beveled, as shown at 26, so as to fit snugly against the beveled or inclined faces 5 and 8 of the door frame and, if desired, a strip 15 of packing material such as indicated at 27 and which may be made of felt or the like, can be arranged along the outer face of the door 25 closed to the beveled faces 26 so as to bear outwardly against the flanges 4, 6 20 and 7 and thus seal the connection between the door and the door frame when said door is properly secured in closed position.

Brackets 28 are secured to the lower portion of each door 25 close to the sides of the door and each bracket has a finger 29 outstanding therefrom and projecting downwardly. These fingers are adapted to engage the lower flange 6 in the door frame and thus hold the lower portion of the door 30 tightly against the flange 6.

Pivotedly mounted upon the upper portion of the door 25 close to the center thereof is a cam 30 having a handle 31 whereby it can be rotated readily, this handle constituting a weight whereby the cam is held normally in position to bear against the flange 7 when the door is moved to closed position. When the door is closed, the fingers 29 engage the lower flange 6 and the cam 30 laps the upper flange 7 and engages the outer surface of said flange, it being possible to rotate the cam 30 by means of handle 31 and in the direction of the arrow in Fig. 1 for the purpose of binding the upper edge of the door tightly against the inner face of the flange 7. With the door thus secured in place, it will be seen that the yoke 23 and the bar 19 can be used as ladder rungs and this bar and the yoke can be spaced apart 50 any desired distance so that the proper intervals between the rungs of the ladder formed by the several doors and their attachments will be substantially uniform.

When it is desired to open the door, the handle 31 is swung so as to disengage the cam 30 from the flange 7. The upper end of the door is then pressed inwardly and the lower edge of the door will, consequently, slide upwardly along the flanges 4, thus 60 withdrawing the fingers 29 from engagement with the flange 6. This upward sliding movement will continue until the lower portion of the door 25 is swung upwardly against the yoke 23 whereupon further downward swinging movement of the upper

portion of the door relative to the bail 13 will be limited and the door will thus be suspended within the silo where it cannot drop upon any person in the silo. After the door has been pressed inwardly to the position 70 described, it can be swung upwardly bodily with the bail 13 and about the extensions 15 as pivots, this movement resulting in the upper ends of the arms 14 riding along the inner curved sides of the ears 11 until the arms 75 pass the upper ends of the ears whereupon said arms will spring outwardly to position above the seats 12. By then releasing the door, the arms 14 will gravitate down onto the seats 12 so that the door will thus be 80 suspended in elevated position as shown in Fig. 4.

The inward movement of the arms 14 while passing between the ears 11 is permitted in view of the fact that the inwardly 85 extended portion 16-18 of one of the arms 14 extends through a loop 21.

When it is desired to close the door, the bar 19 is pushed downwardly so that it will ride upon one or both of the obliquely disposed portions 18, thus partly withdrawing the terminals 15 from the lugs 9. It is of course necessary first to push the door upwardly to a slight extent so as to disengage the arms 14 from the seats 12 before the bar 95 19 is shifted in the manner described. This movement of the arms 14 toward each other will be sufficient to disengage them from the ears 11 and the bail 13 together with the door 25 can then be swung downwardly 100 until the lower edge of the door 25 comes against the flanges 4, the door moving downwardly in an arc such as outlined by the dotted lines in Fig. 4. It will be seen that during this lowering of the door there is 105 no danger of its becoming disconnected and falling downwardly into the silo. As soon as the door has been lowered in the manner described, the upper end thereof is swung forwardly toward the door frame but, as the handle 31, which constitutes a weight, normally hangs downwardly, it will be seen that the upper end of cam 30 will strike against the flange 7 and the door will thus be prevented from completely closing. The 110 fingers 29, however, will engage the flange 6 when the front end of the door is swung outwardly. As soon as the cam comes against flange 7, handle 31 is shifted to disengage the cam from the flange, whereupon the door can be drawn forward into the door frame and the cam shifted in the direction indicated by the arrow in Fig. 1, the movement of the cam being such as to cause the sides, top and bottom of the door to bind 115 tightly upon the flanges in the door frame.

Ears 32 may be extended from the sides of the door frame and constitute means for connecting the upper end of a chute to the frame.

What is claimed is:—

1. The combination with a door frame and a door, of a bail having its lower or intermediate portion connected to the lower portion of the door and its ends connected to the upper portion of the frame, said intermediate portion outstanding to limit the inward swinging movement of the door relative to the bail.
- 10 2. The combination with a door frame and a door, of a bail connected to the upper portion of the door frame and to the lower portion of the door, said bail having means outstanding therefrom for limiting the inward swinging movement of the door relative to the bail, said outstanding portion constituting a ladder rung when the door is closed, and means upon the door frame and coöperating with the bail for supporting the bail and door in open position.
- 15 3. The combination with a door frame and a door, of a bail connecting the lower portion of the door to the upper portion of the frame, means upon the frame for engaging the sides of the bail to support the door and bail in open position, and means connecting the sides of the bails and coöperating therewith for disengaging said sides from the supporting means.
- 20 4. The combination with a door frame and a door, of a bail constituting a connection between the lower portion of the door and the upper portion of the frame, the sides of said bail having obliquely disposed deflecting portions, means upon the door for engagement by the sides of the bail to support the door in open position, and a cross member movably engaging said deflecting portions at the sides of the bail and coöperating therewith to disengage the sides from the supporting means.
- 25 5. The combination with a door frame, a door and means upon the upper and lower portions respectively of the door for engaging the frame to hold the door in closed position, of a bail constituting a connection between the lower portion of the door and the upper portion of the frame, the sides of the bail being shiftable toward each
- 30 other, means upon the frame and in the paths of the sides of the bail for engagement by said sides to support the door in open position, and a cross member carried by said sides and coöperating therewith to disengage the sides from the supporting means.
- 35 6. The combination with a door frame and a door, of a bail connecting the lower portion of the door to the upper portion of the frame, means upon the bail and coöperating with the door for holding said door in an intermediate open position, means
- 40 upon the frame and coöperating with the bail for holding the door entirely open.
- 45 7. The combination with a door frame and a door, of a bail connecting the lower portion of the door to the upper portion of the frame, means upon the bail and coöperating with the door for holding said door in an intermediate open position, means
- 50 upon the frame and coöperating with the bail for holding the door entirely open, and a cross member engaging opposed sides of the bail and coöperating therewith to disengage the bail from the holding means
- 55 upon the door frame, said cross member and the first named means forming ladder rungs when the door is closed.
- 60 8. The combination with a door frame and a door, of a bail connecting the lower portion of the door to the upper portion of the frame, said bail having inwardly movable side portions slidably and revolubly engaging the door frame, deflecting ears extending inwardly from the door frame and into the paths of the sides of the bail, said ears forming seats for the sides of the bail when the door is raised to open position.
- 65 9. The combination with a door frame and a door, of a bail connecting the lower portion of the door to the upper portion of the frame, said bail having inwardly movable side portions slidably and revolubly engaging the door frame, deflecting ears extending inwardly from the door frame and into the paths of the sides of the bail, said ears forming seats for the sides of the bail when the door is raised to open position, and means mounted upon the side portions of the bail for disengaging said side portions from the seats.
- 70 10. The combination with a door frame and a door, of a bail connecting the lower portion of the door to the upper portion of the frame, said bail having inwardly movable side portions slidably and revolubly engaging the door frame, deflecting ears extending inwardly from the door frame and into the paths of the sides of the bail, said ears forming seats for the sides of the bail when the door is raised to open position, said side portions of the bail having obliquely disposed deflecting portions, and a cross bar movably engaging said deflecting portions and coöperating therewith to shift the side portions of the bail toward each other and out of engagement with the seats.
- 75 In testimony that I claim the foregoing as my own, I have hereto affixed my signature in the presence of two witnesses.
